Teis Pittys

UNITED STATES PATENT OFFICE.

JAMES G. MACLAREN, OF SYRACUSE, NEW YORK, ASSIGNOR, BY MESNE ASSIGNMENTS, TO THE LAMSON COMPANY, A CORPORATION OF MASSACHUSETTS.

DISTRIBUTING APPARATUS FOR CONVEYER SYSTEMS.

Original application filed March 26, 1920, Serial No. 369,084. Renewed March 9, 1925. Divided and this application filed March 11, 1925. Serial No. 14,693.

To all whom it may concern:

Be it known that I, JAMES G. MACLAREN, a citizen of the United States of America, and resident of Syracuse, in the county of Onondaga and State of New York, have invented new and useful Improvements in Distributing Apparatus for Conveyer Systems, of which the following is a specification.

10 This invention relates to conveyer systems and more particularly to apparatus for distributing articles to various parts of a system in such a manner as to avoid undue accumulation of articles or clogging at any 15 particular point, and while primarily intended for embodiment in the central station of a pneumatic despatch system is not necessarily restricted to such specific use,—the present application being a division of my 20 pending application Serial No. 369,084, filed March 26, 1920, renewed March 9, 1925.

In the accompanying drawings a preferred embodiment of the invention is illustrated by way of example.

25 Fig. 1 being a fragmentary side elevation partly in section of one end of a conveyer apparatus embodying the invention; and

Fig. 2 being a vertical section on the line 2—2 of Fig. 1.

30 Referring to the drawings the numeral 1 indicates any suitable table or support, for example the operator's desk of the central station of a pneumatic despatch system. This table or desk 1 supports a series of 35 spaced vertical partitions 2, 3, 4 and 5 the number of such partitions being greater or less in accordance with the desired capacity of the apparatus. The spaces between adjacent partitions are closed at their tops by 40 floor members 6, 7 and 8, respectively. These floor members are substantially horizontal and preferably extend from one end to the other of the desk structure.

45 The floor members 6, 7, and 8 support the upper runs 9, 10 and 11 respectively of endless belt conveyers, whose lower runs conveniently rest upon and are supported by the table 1. The floor members 6, 7 and 8 are preferably arranged at progressively increasing heights above the table 1 so that the upper runs 9, 10 and 11 of the belt conveyers are disposed in stepped relation, the forward belt, as here illustrated, being the low-

est and succeeding belts being at higher levels.

55 The several belts pass about pulleys 12, 13 and 14 respectively which, as here shown, are mounted upon parallel shafts, although it is contemplated that they may be mounted upon the same shaft if desired. At their 60 other ends the belts may be similarly supported and they are driven in the direction of the arrow A in Fig. 1 by any suitable drive means, not shown.

65 The front vertical wall or partition 2 is extended above the belt 6 to provide the retaining wall 15 which preferably extends to a height at least as great as that of the uppermost belt 11.

70 The partitions 3 and 4 also extend above the floor members 7 and 8 respectively, and the partition 5 extends above the floor 8. These upwardly extending partitions thus constitute the side walls of parallel trough-like guideways whose floors are formed respectively by the belts 9, 10 and 11. Preferably the partitions 3 and 4 terminate in outwardly deflected portions 16 and 16' respectively, whose edges are turned or inclined downwardly as indicated at 17 and 80 17' respectively to overhang the floors 6 and 7.

75 One or more article delivery means, for example, pneumatic despatch terminals 19 are arranged to deliver articles, such for 85 example as cash carriers, onto the belt 11 while similar or different delivery means, for example the pneumatic despatch terminals 20 and 20', is arranged to deliver articles onto the belt 9. The delivery terminals 19 are preferably disposed in a plane offset from the vertical plane 24 of the center of the belt 11 so that articles delivered through said terminals tend to fall upon the belt 11 at a point near that edge thereof 90 which is disposed adjacent to the next lower belt. Similarly the terminals 20 and 20' are disposed to one side of the central vertical plane 23 of the belt 10. One or more of the terminals 19, 20 etc., is preferably arranged 95 to turn about its own vertical axis so that the guide spout 21 at its lower end may be disposed as shown in Fig. 1, or alternatively as shown in dotted lines at 22 in Fig. 2.

100 At the delivery end of each belt there is 105 arranged a hopper 26 for receiving carriers

delivered from the end of the belt. In Fig. 1, but a single hopper is illustrated it being understood that similar hoppers are provided for the belts 10 and 11. Each hopper 5 delivers the articles which are fed into it into a tube 27 which in turn delivers them to a corresponding selector device 28 where the articles are sorted into classes in accordance with some distinguishing characteristic. 10 For example, if the articles be cash carriers of the type used in pneumatic despatch systems this separation may be in accordance with the shape or configuration of the head of the carrier. The articles so segregated 15 are delivered into the tubes 29 and 30 respectively. These tubes 29 and 30 may be of any desired length and lead to any desired point of discharge.

As herein illustrated the tube 30 is provided at its delivery end with a receptacle of tubular construction comprising the substantially vertical upper portion 31 and the inclined lower portion 32. The upper portion 31 is furnished with a lateral discharge opening 33, while the inclined portion 32 is furnished with a discharge opening 34 in its upper surface. The discharge openings 33 and 34 are at opposite sides of the receptacle as illustrated in Fig. 1.

30 At the lower end of the receptacle a stop member or shelf 35 is provided. This shelf is so positioned that a carrier 36 resting thereon is readily accessible through the opening 34 for removal by the operator. 35 The upper and lower parts of the receptacle are so proportioned that when a carrier rests upon the shelf 35 its upper end is positioned approximately at the level of the lower edge of the opening 33. If, before a 40 carrier 36 resting upon the shelf 35 has been removed by the operator, a second carrier 38 is delivered into the receptacle, such second carrier will engage the head of the carrier 36 substantially at the point 37 and as 45 the point of engagement is eccentric to the axis of the carrier 38 the latter is caused to topple out through the opening 33.

50 Preferably a conveyer belt 39, running in a suitable trough 40, is disposed beneath the opening 33 so that articles delivered through the latter will fall upon the belt and be conveyed to some convenient point.

The operation of the device is substantially as follows, it being assumed for convenience in description that the articles to be handled are cash carriers of the usual form employed in pneumatic despatch systems. If a carrier be delivered through the terminal 19 it falls upon the belt 8 and is 55 rapidly conveyed toward the corresponding hopper 26. If during its travel beneath the terminal 19 another carrier should be delivered so as to fall upon the first carrier, such second carrier would land in the position indicated at 26 in Fig. 2 where it would

roll outwardly and downwardly over the inclined guiding apron 17, onto the next lower belt as the apron deflects the rolling carrier toward the outer or forward edge of the next lower belt, it will roll over a carrier always resting upon said latter belt and disposed in its path and will continue down onto the next lower guideway. This arrangement prevents accidental piling up of carriers upon one of the upper belts which might occasion clogging of the receiving hopper or possibly the dropping of a carrier from the receiving hopper. While carriers are herein mentioned, it is evident that an excessive quantity of material of any kind, 70 deposited upon an upper belt will tend to spill over onto a lower belt, thus automatically distributing the load. The belts are preferably run at such a speed as to space successive articles sufficiently to permit the separator device 28 to operate properly without jamming.

75 By turning one or more of the delivery terminals 19, etc. into the position indicated at 22 in Fig. 2, carriers may be delivered directly onto a belt adjacent to the one upon which they normally would be delivered. Thus if there be a special sale in one department of the establishment served by the appliance, the increase volume of carriers delivered through any particular set of tubes may be cared for without congestion at the central station by setting the delivery terminals so that carriers from one or more of the delivery terminals will be transmitted to operators who do not ordinarily serve these particular tubes.

80 Furthermore if the arrangement just described does not suffice to distribute the carriers to a sufficient number of operators, the arrangement shown at the lower part of Fig. 1 may be employed to assist in such distribution. For example, if the operator located at the receptacle 31 is unable to remove carriers from the shelf 35 as fast 85 as received, surplus carriers are automatically delivered upon the belt 39 and thus carried to another operator's station or otherwise disposed of, so as to relieve the congestion. If the operator at the station 90 served by the tube 30 should be called away temporarily, a dummy carrier may be placed in the position of the carrier 36 of Fig. 1 which will result in deflecting all incoming carriers onto the belt 39 by means of which 95 they are carried to another station or delivery point.

100 While I have described the device as embodied in the central station apparatus of a pneumatic despatch system, it is evident that in many of its broader aspects it is applicable to conveyer systems in general and without reference to the particular type of article which is to be conveyed. It is furthermore to be understood that while a dis- 105

tributor such as that indicated at 28 may be employed, particularly when the apparatus is used in connection with a pneumatic despatch system, such distributor may be dispensed with if desired without substantially affecting the operation of the other parts of the device.

It is also clear that by lengthening the lower part 32 of the receptacle at the lower end of tube 30, a greater number of articles may be supported therein at the same time.

In illustrating the invention I have shown three belt conveyers disposed in stepped relation, but I contemplate that a greater or less number may be employed and that under some circumstances the successive belts may first increase progressively in height above the table and then decrease in height toward the opposite side of the table. It is further to be understood that the delivery terminals 19, etc. are merely emblematic of any desired form of delivery means and that other means, such for example as belt conveyers, gravity chutes, etc. might well be substituted under proper circumstances.

I claim:

1. A conveyer system comprising a plurality of conveyer belts arranged side by side and in vertically stepped rotation, and means for delivering articles to said belts, the delivery means for each belt being so disposed as to deliver articles at a point nearer to the next lower belt than to the next more elevated belt.

2. A conveyer system comprising a plurality of parallel trough-like guideways disposed at different levels in stepped arrangement, a belt conveyer forming the floor of each guideway, and means for delivering articles into the upper of said guideways, said delivering means being so disposed relatively to the central longitudinal axis of the guideway that an article deposited upon another article already resting upon the conveyer belt tends to roll down onto the belt of the adjacent lower guideway.

3. A conveyer system comprising a plurality of parallel trough-like guideways, said guideways being disposed at different levels in stepped arrangement, one side wall of an upper guideway inclining outwardly to overhang the next lower guideway.

4. A conveyer system comprising means providing a plurality of parallel guideways along which articles may move, said guideways being at different levels, and means for delivering articles to said guideways at points spaced longitudinally of the latter, said delivery means being so disposed relatively to the center lines of the respective guideways that an article falling upon another previously deposited on the guideway tends to spill over into the next lower guideway.

5. A conveyer system comprising a plurality of parallel trough-like guideways, said guideways being at different levels, means for moving articles deposited within the guideways longitudinally of the latter, and means for depositing articles in one at least of the upper guideways at a point between the longitudinal center line of such guideway and that margin thereof disposed adjacent to the next lower guideway.

6. A conveyer system comprising a plurality of parallel guideways, each guideway being separated from the adjacent guideway by a division wall, the upper parts of said walls being flared outwardly away from one guideway and overhanging the next guideway.

7. A conveyer system comprising a plurality of parallel trough-like guideways disposed at different levels in stepped arrangement, adjacent guideways being separated by division walls, the upper part of each division wall being flared outwardly and then downwardly to overhang the lower guideway of a pair.

8. A conveyer system comprising a plurality of spaced vertical walls, said walls being of progressively greater height from one end of the series to the other, and an endless belt conveyer disposed within the space between each pair of adjacent walls, the upper runs of said conveyers being disposed at progressively higher levels from one end of the series to the other and constituting the floors of trough-like guideways.

9. A conveyer system comprising a plurality of belt conveyers disposed in parallel relation, means for delivering articles of various classes indiscriminately to each of said conveyers, means disposed at the end of each conveyer for receiving articles therefrom and for segregating said articles according to their respective classes, and a receptacle for articles of one class in which such articles may come to rest.

10. A conveyer system comprising a plurality of parallel belt conveyers disposed at different levels in stepped arrangement, means for feeding articles to said conveyer, excess articles spilling from upper conveyers to those at lower levels, a receiving hopper at the end of each conveyer, a guide leading from the hopper, and a receiver at the end of the guide in which articles may come to rest.

11. A conveyer system comprising a belt conveyer for conveying articles of different kinds, a receiving hopper at the delivery end of the conveyer, a receptacle having delivery openings at different heights, and means for guiding articles received by the hopper to a separator for separating the articles according to their respective kinds and delivering articles of one kind only to the receptacle, articles entering the latter

normally passing the upper opening and coming to rest near the lower opening.

12. A conveyer system comprising a conveyer for articles, a receptacle provided with vertically spaced delivery openings, means for directing articles delivered by the conveyer to the upper end of the receptacle, said articles normally passing the upper delivery opening, and a shelf for supporting such articles adjacent to the lower opening, an article so supported operating to deflect following articles through the other opening.

13. A conveyer system comprising a receptacle for carriers, said receptacle having angularly disposed parts each provided with a discharge opening, and means for supporting one or more articles in one of said parts in such a position that further articles entering the receptacle will engage an article resting therein and fall out through the opening in the other part.

14. A conveyer system comprising means for moving cylindrical carriers, a receptacle into which carriers are delivered successively, said receptacle comprising a substantially vertical upper part and an inclined lower part, each part having a discharge opening, and means for supporting a carrier in the lower part of the receptacle in such a position that another carrier, striking the upper end of first named carrier, will topple out through the delivery opening in the upper part.

15. A conveyer system comprising a receptacle for cylindrical carriers, said receptacle having a substantially vertical upper portion and an inclined lower portion, both

portions having lateral delivery openings, said openings being at opposite sides of the 40 receptacles, and a supporting shelf at the lower end of the lower part of the receptacle for retaining a carrier in a position where it is accessible through the lower opening and with its upper end positioned to obstruct 45 a following carrier and cause it to topple out through the upper opening.

16. A conveyer system comprising a receptacle for cylindrical carriers, said receptacle having a tubular upper portion providing 50 a free and unobstructed passage for carriers, said upper portion having a delivery opening in its side and a tubular lower portion inclined away from the apertured side of the upper portion, and a stop at the lower 55 end of the lower portion positioned to arrest a carrier in such a position that it obstructs the passage through the receptacle and thereby causes a following carrier to topple out through the delivery opening. 60

17. A conveyer system comprising means for moving like carriers in succession, a receptacle into which such carriers are delivered, said receptacle providing a free and unobstructed passage for carriers, the receptacle having a plurality of delivery openings, means for retaining a carrier within the receptacle in a position where it is accessible for removal through one delivery 65 opening, and means disposed to receive carriers delivered through the other opening 70 and to carry them away from the receptacle.

Signed by me at Syracuse, New York, this 28th day of February, 1925.

JAMES G. MACLAREN.
